DESIGN FOR A PICTURE FRAME

Hjalmar Rekens, New York, N. Y.

Application July 6, 1936, Serial No. 63,665

Term of patent 7 years

To all whom it may concern:

Be it known that I, Hjalmar Rekens, a citizen of the United States, residing at New York city, in the county of New York and State of New York, have invented a new, original, and ornamental Design for a Picture Frame, of which the following is a specification, reference being had to the accompanying drawing, forming a part thereof.

Fig. 1 is a rear elevational view of a picture frame showing my new design.

Fig. 2 is a side elevational view of the same, looking in the direction of the arrows of the line 2—2 of Fig. 1.

Fig. 3 is a bottom edge view of the same, looking in the direction of the arrows of line 3—3 of Fig. 1.

Fig. 4 is a perspective front view of the same. The dominant feature of my design resides in the back of the picture frame.

I claim:

The ornamental design for a picture frame, as shown and described.

In testimony whereof I have affixed my signature.

HJALMAR REKENS.
